UNITED STATES PATENT OFFICE.

GEORGE M. DEPEW, OF CANANDAIGUA, NEW YORK, ASSIGNOR TO GEORGE V. WILLSON, OF PITTSBURG, PENNSYLVANIA.

WIRE-SPIRALING MACHINE.

SPECIFICATION forming part of Letters Patent No. 717,552, dated January 6, 1903.

Application filed June 6, 1901. Renewed June 12, 1902. Serial No. 111,328. (No model.)

To all whom it may concern:

Be it known that I, GEORGE M. DEPEW, a citizen of the United States of America, residing in Canandaigua, in the county of Ontario, 5 in the State of New York, have invented a certain new and useful Improvement in Wire-Spiraling Machines, of which the following is a true and exact description, reference being had to the accompanying drawings, which 10 form a part thereof.

My invention relates to machinery for bending wire into a spiral form, my object being to provide a simple and efficient machine for this purpose.

15 The essential feature of my invention consists in the combination of a revolving perforated spindle having set or formed in its perforation bending-shoulders with means for feeding a wire through the perforated and 20 rotating spindle.

Reference being now had to the drawings, in which my invention is illustrated, Figure 1 is a plan view showing my twisting mechanism in simple form. Fig. 2 is an enlarged 25 plan showing the spindle in longitudinal central section. Fig. 3 is a vertical section taken on the line 3 3 of Fig. 2, and Fig. 4 is a view illustrating the action of the bending shoulders or pins upon the wire.

30 A indicates the frame of the machine; B B, the bearings for the perforated spindle.

C C are the bearings for the driving-shaft; D D, bearings for the feed-rolls.

E is the driving-shaft, to which motion is 35 imparted in any convenient way, this shaft having attached to it a gear-wheel E' and a bevel-gear E².

40 F and f indicate the shafts supporting the feed-rolls. To the lower shaft F is attached the bevel-wheel F', driven by the bevel-wheel E², and the said shaft has also attached to it a gear-wheel lying immediately below and corresponding in size with the gear-wheel f², through which it drives the upper shaft f.

45 F³ f³ indicate the feed-rolls, attached to the shaft and through which the wire is fed to the bending mechanism proper.

G is the revolving spindle, supported in the

bearings B B and having attached to it a gear-wheel G', engaged and driven by the 50 gear-wheel E'. The outer end of the spindle proper is externally threaded, as indicated at G³, and the spindle is centrally perforated, as indicated at G².

H is a prolongation of the spindle having 55 a threaded end H', which screws onto the end G³ of the spindle G, and a perforation H², which registers with the perforation G². The outer end of this prolongation of the spindle is, as shown, internally threaded, as indicated at H³, and the internal perforation H² is interrupted by shoulders formed, as shown, by steel pins I I, so arranged that a wire in passing through the spindle is necessarily bent in order to pass the shoulders formed by 60 the pins I.

J is a guide-piece screwing into the threaded end H³ of the spindle extension H and lying close to the peripheries of the feed-rolls.

K, Fig. 4, indicates the straight wire, and 70 K' the spirally-bent portion of the wire.

The operation of the device is easily followed. The shaft E being set in motion drives the bending-spindle G H and the feed-rolls F³ f³. The wire K, fed through the feed-rolls and the guide J, is bent as it passes between the bending-shoulders of the pins I, rotating with the spindle. The resulting bend is a perfect spiral, which in the construction illustrated is equivalent to winding the wire 80 around a central line.

Having now described my invention, what I claim as new, and desire to secure by Letters Patent, is—

1. In a wire-twisting machine, a revolving 85 perforated spindle, in combination with bending-shoulders set transversely in the perforation of the spindle and on opposite sides thereof to bend the wire as it passes through said perforation, and means for feeding the wire 90 through the revolving spindle.

2. In a wire-twisting machine, a revolving perforated spindle, in combination with bending-shoulders set transversely in the perforation of the spindle and on opposite sides thereof to bend the wire as it passes through said 95

perforation, and feed-rolls for feeding the wire through the revolving spindle.

3. In a wire-twisting machine, a revolving perforated spindle, in combination with bending-shoulders I, I, I set in the perforation of the spindle as described to bend the wire as it passes through said perforation, and means

for feeding the wire through the revolving spindle.

GEORGE M. DEPEW.
